CASH-REGISTER.

SPECIFICATION forming part of Letters Patent No. 698,967, dated April 29, 1902.

Application filed June 2, 1900. Serial No. 18,868. (No model.)

To all whom it may concern:

Be it known that we, WILHELM KNEHANS, merchant, and FRANZ PÜSCHEL, mechanical engineer, subjects of the German Emperor, residing in the city of Bielefeld, Germany, have invented new and useful Improvements in or Relating to Cash-Register Apparatus, of which the following is a specification.

Our invention relates to cash-registering apparatus in which the release of the drawer and the coupling and uncoupling of the registering mechanism are effected simultaneously by means of a lever. The apparatus is so arranged that the opening of the cash-drawer is impossible without previously operating the keys. For this purpose the lever must be pressed down twice from its normal position. By the first movement of the lever all the register-operating devices are moved back to the zero or normal position, while at the time the cash-drawer remains locked. If now the next amount of cash received is indicated, the release of the locking device is effected. The second downward movement of the lever produces the opening of the cash-drawer. The indicating and registering devices remain unchanged. In this manner the cash-drawer after being locked cannot be opened again before a new operation of the keys and the indicated amount visible to the customer and to the operator until another amount received is indicated.

In the accompanying drawings, Figure 1 is a longitudinal section through the improved cash-register, showing the hand-lever, as well as the mechanism connected with it, in side elevation. Fig. 2 is a rear view of the registering device with its connections with the hand-lever. Fig. 3 represents an enlarged detail isometric view of the heart-shaped groove.

1 indicates the hand-lever, to be operated by the cashier, said lever being pivoted on a rod 2. A spring 3, attached at one end to any suitable part of the casing or frame of the apparatus and at the other end to the inner extremity of the lever 1, tends to draw the latter downward. Near the inner end 4 of the lever 1 is articulated a rod or bar 6, which in

its turn is articulated to a cylindrical bolt 7. 50 This bolt is surrounded by a cylinder 8 in such a manner that it can freely turn in it, but involves the latter in its movement whenever the bolt is axially displaced. The surface of the cylinder is provided with a heart-shaped groove with four points or recesses 9, 10, 11, and 12. The cylinder 8 is surrounded by a cylinder or tubular casing 13, fixed to the frame of the apparatus, the cylinder 8 being arranged in the latter like a piston—i. e., 60 is capable of being moved up and down in it. A pin 21 in the wall of the fixed cylinder 13 engages in the heart-shaped groove in the piston 8. The piston 8 is thus guided when it moves up or down by the heart-shaped groove. 65 The cash-drawer 14 is held in the position represented in the drawings by means of a hook 15, pivoted at 16. This hook engages a bar or projection 17, fixed to the cash-drawer. To the free end of the hook 15 is connected a 70 rod 18, the upper part of which is provided with a longitudinal slot 19. A pin 20 on the part 4 of the lever 1 engages in this slot 19.

The operation and effect of the lever 1 are as follows: When the lever occupying the 75 position as represented in the drawings is pressed down, it will pivot around its axis 2 and its end 4 will ascend. The piston 8 will also rise and at the same time turn in the cylinder 13, owing to the pin 21 engaging the 80 heart-shaped groove in the piston. The distance to which the lever end 4 can rise is equal to the vertical distance between the points 9 and 10. It is clear, therefore, that the lever 1 can only be so far depressed until the 85 point 10 comes against the pin 21. The pin 20 on the part 4 of the lever 1 ascends simultaneously, but only to the top of the slot 19, and the rod 18 is consequently not raised. Thus the movement of the pin 20 does not affect during the first movement of the lever the rod 18 and hook 15—i. e., the cash-drawer remains locked. When the lever 1 is released, its inner end will again descend under the influence of the spring 3, while the pin 95 21 enters the recess 11 of the heart-shaped groove. In consequence of this the lever 1 will not return to its original position.

Through this first movement of the lever the indicating devices are brought back to the zero position in a manner to be described hereinafter. After the first depression and release of the lever it remains stationary, as described above, and allows the cashier to indicate the new amount paid in. This having been done, the lever 1 is pressed down a second time. By this second depression of the lever the cash-drawer is released and opened. This is effected in the following manner: By pressing down the lever a second time the end 4 of the lever rises again. Since the pin 21 now passes along the arc 11 12 of the heart-shaped groove, the piston 8 is correspondingly turned in the cylinder 13, and the end 4 of the lever can rise until the recess 12 comes against the pin 21. As the recess 12 is lower than the recess 10, the piston can move to a correspondingly greater height in the cylinder 13, and consequently during this second movement of the lever the pin 20 will strike against the upper end of the slotted bar 18 and raise it. In consequence of this the free end of the hook 15 will be raised and the hook will turn about its pivot 16. The hook 15 is thus disengaged from the bar 17 and the cash-drawer becomes unlocked. Springs (not represented in the accompanying drawings) effect an automatic opening of the drawer in the usual manner, so that the bar 17 moves out of reach of the hook 15. The lever 1 being released after its second downward pressure, the free end of the lever is again drawn downward by the spring 3 and the piston 8 moves down with it, the pin 21 passing along the curve 12 9 of the heart-shaped groove until it arrives again at its first position, as represented in the accompanying drawings. The hook 15 and the rod 18 are so arranged that the pin 20 never reaches the bottom of the slot 19, there always remaining a certain free space. The object of this is as follows: When after placing the amount received into the opened cash-drawer the latter is pushed back again, the bar 17 comes in contact with the end of the hook 15 and, raising it slightly, passes below it, and in order that this raising should be possible the said free vertical space is provided. After pushing the drawer fully in the hook 15 engages again over the bar 17, in consequence of which the bar, and with it the drawer, is again locked. The operating-keys consist of slides, each of which is provided with an index set according to a corresponding scale. One of these slides, which in all respects are similar to each other, is represented in the accompanying drawings. The slide 22 can be displaced and set by the cashier by means of a handle 23. For fixing the slide locking-teeth 24 24 are provided on the under side of the slide, which teeth as the slide is drawn forward slide over the vertical end of a hook or catch 25, pivoted at 26 and drawn or pressed upward by means of a spring 38. The slide is guided over rollers 27 28, and a spring 39

tends to draw the slide inward. At its front end the slide is provided with a sleeve 29, containing a pin 30, provided on the top with a roller 31 and supported or pressed by a spring in such a manner as to allow the pin 30 to yield in a vertical direction. In this manner the slide is not only guided in a straight line, but also elastically pressed against its guiding device. Owing to this spring-controlled pressure, the teeth 24 24 can pass when the slide is drawn forward—i.e., from left to right in the drawings—over the vertical shank of the hook 25, being correspondingly raised when the slide is drawn out, while an unintentional pushing in of the slide is impossible. Each slide is provided with a similar hook 25. All the hooks 25 are pivoted about the same shaft 26. In the angle of the hooks 25 is freely arranged a shaft 32, mounted at its ends in slots 50. This shaft is fixedly connected with a latch or lever, the shorter inner end 33 of which presses against a fixed stop or projection 34, while the longer arm 35 is free and provided at its end with an articulated part 36. Opposite to this articulation 36 the lever 1 is provided with a finger 37. The effect of the first downward pressure of the lever from the position represented in the drawings on the slide 22 may be thus explained. Let us suppose that the slide 22 is drawn out. The hook 25 will hold it in the desired position by engaging in the corresponding locking-tooth. If, now, the lever 1 is pressed down, the finger 37 will press down the part 36. Since the end 33 is pressing against the projection 34, this point of contact of the two parts will form the pivot or fulcrum for the lever 33 35, and since the shaft 32 is not fixed, but only mounted in slot-bearings, the shaft will descend also and in doing so will move the hooks 25 downward. The vertical shank of the hook will thereupon be disengaged from the locking-tooth, and the spring 39 will draw the slide back to its zero position. The finger 37 passes over the extreme edge of the hinged part 36, so that this part becomes free and the shaft 32 too. Each hook therefore can be raised again by the spring 38, owing to which the shaft 32 will also be raised to its former position. Should now the slide 22 be again drawn out for the purpose of indicating a new amount, the locking-teeth 24 24 will slide over the vertical end of the hook 25 and as soon as released will be locked in position by the hook 25, the locking remaining effected also during the second pressing down of the lever. Since the finger 37 is underneath the articulation 36 after the first pressure on the lever, any further pressure downward of the lever and its finger will have no effect as regards the articulation 36. When the lever 1 is released after the second pressure downward, its front end will rise again. The finger will thereupon pass by the articulation 36, the latter giving away and turning on its hinge in the direction opposite to that of the movement of the watch-hand,

without, however, influencing the lever 35. In consequence of this the amount exhibited on the indicator remains stationary and visible until another amount is to be indicated.

5 Each of the slides 22 is formed or provided on its upper side with a rack, the teeth 40 of which gear with the tooth-wheel 41, gearing with another tooth-wheel 42, and this with a tooth-wheel 43. The toothed wheels 43 are 10 loosely mounted upon a sleeve turning upon the shaft 44. The sleeve is provided with pins, against which strike studs projecting laterally from toothed wheels 43. Upon the sleeve is fixed a sector-shaped cam 45, turning with the sleeve when one of the toothed wheels rotates. The cam 45 actuates a lever 46 47, pivoted at 48, the other end of which 15 effects the locking of the cash-drawer. The object and effect of the cam 45 and the levers 20 46 and 47 will be clear from the following explanation:

When the slide 22 is in the position represented in the accompanying drawings and indicates the zero position, the position of the 25 cam as regards the lever 46 is such that the latter, as represented in the drawings, is not affected. The free end 47 of the lever is pressed down by a spring 51 in such a manner that it engages in a notch 49 in the side 30 of the cash-drawer. The latter is therefore kept locked in such position by the levers 46 and 47. When, however, a slide 22 is drawn forward—*i. e.*, from the left to right—the corresponding toothed wheel 43, and with it the 35 cam 45, is turned in the direction indicated by the arrow. In the course of this movement the cam presses down the upper end of the lever 46, owing to which the other end 47 of the lever is withdrawn from the notch 49 and 40 the drawer is unlocked. It is clear that the cash-drawer cannot be opened until the movement of the cam has been effected—*i. e.*, until a new amount has been indicated. In this manner any attempt to avoid indicating is 45 rendered impossible. With the actuation of the indicator devices the registering mechanism is simultaneously operated. This is effected in the following manner: The toothed wheels 43, gearing with other toothed wheels 50 52, which are fixably connected with the indicator 53, also engage with the toothed wheels 54 of the registering mechanism. The latter is arranged on a shaft 55, on which it is longitudinally movable. Suitably arranged in 55 movable connection with the slidable frame of the registering device is a bar 56, Fig. 2, articulated to a bell-crank lever 57 58, mounted on a fixed pivot 59. A spring 60 is fixed at one end to a suitable part of the frame of 60 the apparatus and at the other to one arm of the bell-crank lever 57 58 in such a manner as to tend to uncouple the toothed wheels 54 of the registering mechanism from the toothed wheels 43 by laterally displacing the former 65 lengthwise on the shaft 55. At the side of the end of the hand-lever 1 is provided a catch or projection 61, carrying at its free end an articulated catch 62, supported by a spring.

The effect of the hand-lever 1 on the registering mechanism is as follows: In the position as represented in Figs. 1 and 2 the lever 1 does not affect the bell-crank lever 57 58—*i. e.*, the registering mechanism is out of operation. By pressing down the lever 1 for the first time its inner end, and with it the projection 61, ascends. In doing so the spring-controlled catch 62 strikes against the arm 58 of the bell-crank lever 57 58 without moving it, since the catch is articulated and gives way as it passes. The catch 61 ascends until 70 the recessed part 10 of the heart-shaped curve strikes against the pin 21, Fig. 1. On releasing now the lever 1 its inner end will descend until the recessed part 11 of the heart-shaped groove strikes against the pin 21. With it 75 descends also the projection 61 and the catch 62. The measurements are so determined that the catch 62 will press the bell-crank lever downward and keep it in that position as long as the pin 21 is in the recess 11. By thus 80 pressing down the arm 58 of the bell-crank lever the bar 56 moves the frame of the registering mechanism longitudinally upon the shaft 55, bringing the wheel 54 into mesh with the toothed wheels 43. The position of the 85 lever when the pin 21 is in the recess 11 is now, as has been described above, the same as that in which the slides 5 are operated. From this it follows that the registering mechanism is operated when the amount taken is 90 indicated. On pressing down the lever 1 a second time the cash-drawer is opened. At the same time the end of the lever 1 and the projection 61 rise, and the pin 21 engages in the recess 12 of the heart-shaped groove. On 95 releasing the lever the catch descends and passes over the extreme end of the arm 58 until it reaches the position represented in Fig. 2. Since the slides 22 remain stationary during that time, the registering mechanism 100 cannot be affected. If now the slides 22 are again set back to the zero position, the lever 1 again receiving the first pressure downward from its initial position the registering mechanism remains out of action. The last-registered amount remains, therefore, indicated, and to it the new amount will be registered 105 in due course.

Having now described our invention, what we claim as new, and desire to secure by Letters Patent, is—

1. In a cash-registering apparatus, the combination of a registering mechanism, an indicating mechanism, a cash-drawer, an actuating-lever, means controlled thereby for releasing the registering devices, means for keeping the drawer locked until the amount of cash is indicated by the indicator, and means for releasing said drawer-locking means carried by said actuating-lever, substantially as described.
2. In a cash-registering apparatus, the com-

bination of a registering mechanism, an indicator and a cash-drawer, an actuating-lever, means controlled thereby for operating the registering mechanism, means for locking the drawer, means for preventing the release thereof when indicating the amount of cash by the indicator, and means for releasing the cash-drawer on a subsequent further depression of the actuating-lever, substantially as described.

3. In a cash-registering apparatus, the combination with an indicating mechanism of an operating-lever, means controlled thereby for operating the indicating mechanism, means for locking the operating-lever against a full downward stroke at one operation, and means for releasing said lever for moving the remainder of the stroke after the indicating mechanism has been reset by the first portion of the stroke of said lever, substantially as described.

4. In a cash-register apparatus, the combination with an operating-lever of a piston for regulating the movement of said lever, having a heart-shaped groove, and a fixed pin on the frame of the register for engaging the latter so as to limit the movement of the piston, substantially as described.

5. In a cash-registering apparatus, the combination with a cash-drawer and an operating-lever, of a piston having an approximately heart-shaped groove and a fixed pin on the frame of the register engaging the said groove, a hook for locking the cash-drawer, a pin-and-slot connection between the operating-lever and the said hook for permitting a partial movement of the lever without releasing the hook, substantially as described.

6. In a cash-register apparatus the combination with indicating devices and an operating-lever, of catches for locking the indicating devices, means for disengaging the catches, a shaft having an arm provided with an articulated part and a finger on the operating-lever co-operating with the articulated part, whereby said arm will be actuated when the lever is moved in one direction, but not when reversed, substantially as described.

7. In a cash-register apparatus the combination with indicating devices and an operating-lever, of a piston having a heart-shaped groove, and a fixed pin engaging the latter, catches for locking indicating devices, means for disengaging the catches comprising a shaft having an arm provided with an articulated part, and a finger on the operating-lever co-operating with the articulated part, substantially as described.

8. In a cash-register apparatus the combination with indicating devices, a cash-drawer and an operating-lever, of a piston having a heart-shaped groove, and a pin engaging the latter, a hook for locking the drawer, a pin-and-slot connection between the operating-

lever and the hook for locking the drawer, catches for locking the indicating devices, means for disengaging the catches and acted upon by the operating-lever, a shaft having an arm provided with an articulated part, and a finger on the operating-lever co-operating with the articulated part, substantially as described.

9. In a cash-registering apparatus, the combination of an indicating mechanism, a registering mechanism, an operating-lever, a spring-actuated bell-crank lever normally retaining the registering mechanism and the indicating mechanism in an uncoupled condition, and a spring-controlled catch projecting laterally from the operating-lever and designed to strike one arm of the bell-crank lever for moving said bell-crank lever for effecting the coupling of the said mechanisms, substantially as described.

10. In a cash-registering apparatus, the combination with an indicating device, an actuating-lever, and a cash-drawer having a notch in one edge thereof, of means engaging said notch for locking the drawer, a second locking means, means for releasing both locks, and means controlled by said actuating-lever for setting the indicating device before the release of said locks, substantially as described.

11. In a cash-registering apparatus, the combination with a slidably-mounted registering mechanism, an indicating mechanism, and an operating-lever, of an articulated catch carried thereby, means coupling said registering and indicating mechanisms, and means for shifting the registering mechanism for uncoupling said parts, comprising a bell-crank lever adapted to be actuated by said articulated catch, and a bar pivotally connecting said bell-crank lever with the registering mechanism, substantially as described.

12. In a cash-registering apparatus, the combination with an actuating-lever, and an indicating mechanism, of slides provided with teeth on their upper edges for operating said indicating mechanism, locking-teeth on the under edges of said slides, hooks engaging the said locking-teeth, a shaft mounted and laterally movable in the angle of the hooks, a lever carried by said shaft, by which it may be caused to disengage said hooks from said locking-teeth, and means on the actuating-lever for engaging the said shaft-lever, substantially as described.

In testimony whereof we have signed our names to this specification in the presence of two subscribing witnesses.
